UNITED STATES PATENT OFFICE.

FREDERICK J. DREKMEIER, OF BELOIT, WISCONSIN.

AUTOMOBILE CURTAIN.

Application filed September 26, 1921. Serial No. 503,306.

To all whom it may concern:

Be it known that I, FREDERICK J. DREKMEIER, a citizen of the United States, residing at Beloit, in the county of Rock and State of Wisconsin, have invented certain new and useful Improvements in Automobile Curtains; and I do declare the following to be a full, clear, and exact description of the invention, such as will enable others skilled in the art to which it appertains to make and use the same.

My invention relates to improvements in vehicle curtains and more particularly to those designed for use on automobiles, the principal object being to provide extremely novel means for carrying the curtains when not in use and for permitting them to be rapidly positioned at the sides of the body whenever their use is necessary.

In carrying out the above end, a further aim is to provide the body with an upwardly opening curtain pocket, to hinge a normally horizontal arm at the upper end of said pocket, and to attach the side curtains to said arm, so that by swinging the latter upwardly, the curtains will be positioned at the side of the machine, in readiness for securing in place.

In carrying out my invention, the curtain is folded upon itself and said curtain is provided with a portion adapted to swing outwardly and inwardly with the door of the machine; and a further object is to provide an inverted L-shaped rod for supporting this portion of the curtain and connecting it with the door, the horizontal part of said rod being formed of pivotally united sections, so that it will not interfere with folding of the curtain.

With the foregoing in view, the invention resides in the novel construction and association of parts hereinafter described and claimed, the descriptive matter being supplemented by the accompanying drawings.

Figure 1 is a perspective view of an automobile equipped with my invention.

Figure 2 is an enlarged perspective view showing the curtain and its carrying arm detached from and moved upwardly from the vehicle body to more clearly show the relation of parts.

Figure 3 is a perspective view showing the manner of folding the curtains.

Figure 4 is a perspective view showing

the manner in which the curtains are housed in the curtain pockets when not in use.

Figure 5 is a perspective view looking toward the inner side of the curtain when in operative position.

Figure 6 is a transverse sectional view of the automobile body cut through the curtain pocket.

In the drawings above briefly described, the numeral 1 designates a well known form of automobile body having the usual or any preferred top 2 and windshield 3. The body shown is of the touring type and the back 4 of the front seat is of hollow formation to provide a pocket 5 to receive the side curtains 6. Since the construction and mounting of each curtain is the same, only one will be described.

The curtain 6 is formed of any appropriate flexible material and is provided with the desired number of lights 7, the usual, or any suitable fastening 8 being employed for securing said curtain to the vehicle top and body, and to the windshield. At a point adjacent the seat back 4, the curtain is secured by rivets or the like 9 to an arm 10 which stands vertically when the curtains are in use, said arm being hinged at its lower end as shown at 11 so that it may swing downwardly to the upper end of the pocket 5. Any suitable means such as the pivoted latch 12 is employed for holding the arm 10 in vertical position, a latch of this form being preferably used in view of the fact that it may be quickly applied when the curtain must be rapidly placed in condition for use when a storm is approaching.

Normally, when the curtain 6 is not in use, it is folded upon any suitable number of folding lines 13 and is carried in the pocket 5, the arm 10 being then lowered as shown in Figs. 4 and 6. When the use of the curtain is necessary the ring or other suitable handle 14 with which the arm is provided, is grasped and said arm is swung to a vertical position and fastened by the latch 12. Movement of the arm in this manner withdraws the curtain 6 from the pocket and positions it in readiness for unfolding at the side of the vehicle so that it may be secured in place by the fasteners 8. To stiffen the curtain and permit easy folding and unfolding thereof, the upper edge portion of said curtain is preferably provided with

a stiffening rod 15 which is hinged at 16 to the arm 10 and formed of sections pivotally connected at 17 upon the hinge lines 13.

Portions 18 of the curtain 6 are adapted 5 to swing with the front and rear doors of the body 1, said portions being reinforced along one vertical edge and their upper edge, by inverted L-shaped rods 19 whose lower ends are adapted to fit within sockets 10 20 of the upper ends of the doors. It usually happens that the horizontal portion of at least one of the rods 19 will extend across one of the hinge lines 13. When this condition is encountered, said horizontal portion 15 of the rod is formed of two sections pivoted together as at 20 but any suitable means such as a sliding sleeve 21 is employed to hold these sections against pivotal action when the curtain is extended for use, while 20 permitting action of the pivot when the curtain is folded for disposition in the socket 5.

From the foregoing, taken in connection with the accompanying drawings, it will be seen that a very simple and advantageous 25 arrangement has been provided for normally storing the side curtains and for permitting the latter to be quickly applied to operative position whenever their use is necessary.

30 While I have shown the invention in connection with a touring car body and have illustrated the pocket 5 as formed in the back of one of the seats, it is to be understood that my invention is adaptable also to 35 roadster bodies and that the pocket need not in all instances be formed in the seat back. This location is preferable, however, on account of economizing in space.

Since excellent results may be obtained 40 with the details disclosed, these details are preferably followed. It is to be understood, however, that within the scope of the invention as claimed, numerous minor changes

may be made in the form of construction shown and that the invention may be embodied in other forms within the scope of the attached claims. 45

I claim:

1. The combination with a vehicle body provided with an upwardly opening curtain pocket, of a flexible side curtain normally folded and positioned in said pocket, an arm attached to said curtain and normally lying horizontally at the upper end of said pocket, said arm being hinged at one end to the vehicle body at a point adjacent said pocket so as to swing upwardly and withdraw said curtain from said pocket, means for holding said arm in upright position to permit easy unfolding of said curtain, a rod carried by said arm adjacent the other end thereof, said rod extending laterally from said arm and having said curtain secured thereto whereby to support said curtain in an upright position when said arm is in its upright position, and means for securing said curtain in place at the side of the vehicle. 65

2. The combination with a vehicle body, of a transversely swinging arm hingedly mounted at one end to one side of said body 70 and normally extending horizontally inwardly from said side, a flexible side curtain attached to and depending from said arm when the latter is in lowered horizontal position, said arm being adapted to be swung upwardly to upright position to position said curtain upright at the side of said body, a rod hinged to said arm at a point adjacent the other end of the latter, said rod extending laterally from said arm and having said curtain fastened thereto, whereby to support said curtain in upright position when said arm is in its upright position. 75 80

In testimony whereof I have hereunto set my hand.

FREDERICK J. DREKMEIER.
